UNITED STATES PATENT OFFICE

2,572,552

LOAD TRANSFER DEVICE

Donald E. Willard, Danville, Ill.

Application August 21, 1946, Serial No. 692,068

6 Claims. (Cl. 94—8)

1

My invention relates to load transfer devices and, while more particularly intended for use with concrete roadways as a means for transmitting loads between and permitting expanding and contracting movements of the slabs, is also capable of adaptation to concrete slab structures generally, including wall sections, where load transference is an important factor.

In concrete highway construction, for example, it is desirable to transfer loads between and to prevent relative vertical movements of adjoining slabs and thus maintain their top surfaces in coplanar relation. Where common dowels alone are used for these purposes, it has been ascertained that the passage of traffic over the roadway and the upward pressure of the subsoil as affected by the condition of the latter sets up critical, localized pressures in the concrete around the bars adjacent the opposed or joint faces of the slabs. This action, known as funneling, crumbles the concrete around the bar sufficiently to permit definite relative movements of the adjacent slab sections which are objectionable.

It is therefore one object of my invention to provide devices for use with common dowel bars which, in addition to preventing funneling by an efficient distribution of the operating loads, regardless of their direction of movement across the separating member between the slabs, and to reinforcing the joint faces of the slabs against lateral flow due to vertical loads, also has limited contact with the dowels in the critical regions so that adjacent slabs may move freely relative to each other along the length of the roadway without possibility of rust freezing of the devices and bars.

A further object is to devise a reinforcing member which may be arranged in a variety of ways to provide the desired load distribution between the bar and slab and to strengthen the joint face of the slab, but which includes in any case a skeleton-like formation in the funneling region having portions providing bearing for the dowel.

These and further objects of my invention will be set forth in the following specification, reference being had to the accompanying drawings, and the novel means by which said objects are effectuated will be definitely pointed out in the claims.

In the drawings:

Fig. 1 is a sectional elevation of one form of my improved load transfer device, as taken along the line 1—1 in Fig. 2, showing the same in oper-

2

ative relation to the adjoining slabs of a roadway.

Fig. 2 is a view of the device looking in the direction of the arrow 2 in Fig. 1, the slabs being omitted.

Fig. 3 is a plan view of the left hand, reinforcing member of the device as it appears in Fig. 2.

Fig. 4 is a section along the line 4—4 in Fig. 2, the slab being omitted.

Fig. 5 is a sectional elevation similar to Fig. 1, but showing a modified form of the load transfer device.

Fig. 6 is a view of the device shown in Fig. 5 looking in the direction of the arrow 6, the slabs being omitted.

Fig. 7 is a section along the line 7—7 in Fig. 5, the slab being omitted.

Fig. 8 is a plan view of a modified form of the device shown in Fig. 6.

Fig. 9 is a view similar to Fig. 4, but showing a variant method of arranging the bearing plates which transfer load between the dowel bar and slabs.

Fig. 10 is a sectional elevation similar to Fig. 2 showing a further modification of the device.

Fig. 11 is a view of the device shown in Fig. 10 looking in the direction of the arrow 11, the slabs being omitted.

Fig. 12 is a section along the line 12—12 in Fig. 10, the slab being omitted.

Fig. 13 is an end view, partially in section, similar to Fig. 4, showing a modified reinforcing member having the bearing plates arranged to provide a greater area of contact with the dowel bar.

Fig. 14 is a sectional elevation similar to Fig. 1 showing another modification of the device.

Figs. 15 and 16, respectively, are a plan view looking in the direction of the arrow 15 and a section along the line 16—16 in Fig. 14, the slabs being omitted.

Fig. 17 is a sectional elevation similar to Fig. 1 showing another modification of the device.

Figs. 18 and 19, respectively, are a plan view looking in the direction of the arrow 18 and a section along the line 19—19 in Fig. 17, the slabs being omitted.

Fig. 20 is a sectional detail showing a modification of the washers that may be used in any of the load transfer devices.

For purpose of illustration and as exemplifying one use of the improved device, the same will be described in connection with a roadway. It will be understood, however, that the essential conception involved is likewise susceptible of adapta-

tion to structural sections in general, regardless of their composing material, where such sections are subject to expansion and contraction and it is desired to prevent buckling or cracking of adjoining sections by inserting a yielding member therebetween, or where such sections are subject to transverse pressures and it is desired to prevent any funneling action around the dowel or reinforcing bars which extend between adjoining sections.

Referring to Figs. 1 to 4, inclusive, of the drawings, the numerals 10 and 11 designate a pair of adjoining concrete slabs which are spaced by an expansion strip 12. This strip may be composed of a bituminous mixture, such as is now commonly employed in the industry for strips of this nature, or it may be formed of cork or rubber, or the expansion may be accommodated by the so-called metal walled joint in which thin metal walls provide facings for the opposed ends of the slabs, the walls being separated by an air space or other yieldable filling. All of the foregoing expansion members or strips are well known in the art and in and of themselves form no part of the present invention. In any case, it is contemplated that the strip will be arranged so that it will not only yield in response to movements of the slabs, but will be composed of a material that is resistant to water, earth acids, or any other decomposing influences which are commonly met with in use of structures of this type. The thickness of the strip may be varied as desired.

A dowel bar 13 is bridged between and has its opposite ends entered into the slabs 10 and 11, respectively, the intermediate portion of the bar passing through a suitable aperture in the strip 12, thus establishing a characteristic road joint. It will be understood that a plurality of these bars are spaced across the width of the roadway in accordance with standard practice, the spacing being generally dependent on the thickness of the slabs and the diameter of the bars. Preferably, the dowel bars are positioned at mid-depth or in the neutral plane of the slabs, parallel to the top surfaces and normal to the joint faces of the slabs. So far as described, the structure is typical of the so-called common dowel bar method of transferring loads between the slabs.

The invention consists in associating with each dowel bar a pair of reinforcing members which are identical and of a novel type, the members of each pair being located in facing relation on opposite sides of the strip 12 and embedded in the respective slabs. Specifically, each reinforcing member 14 comprises a vertical plate 15 which is embedded in the joint face of the associated slab and is apertured at 16 to receive the dowel bar 13. The lower end of the plate 15 is bent to provide a footing 17 for resting on the subgrade 18 and the end of the footing 17 terminates in a load distributing wing 19 which extends upward into the slab below the dowel bar and may be shaped as desired to provide adequate anchorage in the concrete. The upper end of the plate 15 is bifurcated to provide a pair of load distributing wings 20-20 which are bent out of the plane of the plate for embedment and anchorage in the associated slab above the dowel bar. By reason of the position of the dowel bar in the slabs, it will be obvious that the wings 19 and 20 are disposed in the tension and compression regions of each slab, respectively.

To provide further reinforcement and prevent deterioration of the concrete around the dowel bar adjacent the joint face of each slab, a

skeleton structure 21 extends inwardly of the slab, is firmly connected to the adjacent plate 15 and is symmetrically related to the dowel bar 13. The structure 21 comprises a pair of rib-like bearing plates 22-22 which are diametrically related on opposite sides of and contact the dowel bar in the vertical plane thereof. The outer or joint face ends of the plates 22 are secured, as by welding, to the plate 15, while the inner ends are similarly connected to a washer 23 which encircles and may closely and continuously fit the bar 13, or the inner periphery of the washer may be relieved or cut away in locations 24-24 (see Fig. 4) so that the washer has bearing contact with the bar only adjacent the plates 22, i. e., in location close to the vertical plane which includes the longitudinal axis of the bar. This variant shaping of the washer 23 may also be employed in the modifications of the device presently described.

The expansion strip 12 is assembled with its dowel bars 13 whose number will depend upon the width of the roadway and the spacing of the bars and with each bar having a pair of reinforcing members 14 abutting opposite sides of the strip, all as shown in Fig. 1. To accommodate expanding and contracting movements of the slabs, each dowel bar 13 is greased on one side of the strip 12 and the end of the bar on the same side is partially entered into a sleeve 25 whose remaining portion is filled with a suitable lubricant that is retained by closing the adjacent end of the sleeve as by pinching at 26. Hence, on one side of the strip 12, the concrete forming the slab 11, for example, will not bond to the bar while the lubricant filled space in the sleeve 25 permits expanding and contracting movements of the slabs. The concrete forming the slab 10, for example, bonds directly to the bar 13 on the opposite side of the strip 12. However, it may be preferable to grease both ends of the dowel bar.

The joint structure having been assembled as above described, it is laid with the footings 17 resting on the subgrade 18. The footings have sufficient area to provide a stable support for the assembly until the concrete is poured, but it is desirable to definitely hold the assembly against sidewise movement due to the pouring impact of the concrete by the usual ground locating stakes which may be driven into the ground along the side of the strip 12, or through apertures in the footings.

Under operating conditions, the plate 15 is embedded in and provides lateral support for the concrete at the joint face of the slab adjacent the dowel bar due to its connection with the wings 19 and 20 which are firmly anchored in the slab, while the bearing plates 22 and the washer 23, which in effect constitute an enlargement of the dowel bar, serve to reduce the unit pressure on the adjoining concrete and so reduces the funneling tendency around the bar adjacent the joint face of the slab. The plate 15, bearing plates 22 and washer 23 have bearing contact with the dowel bar 13 and the vertical disposition of the plates 22 insures the most efficient transfer of load between the bar and slab. An outstanding feature of the construction is that while adequate bearing is provided for the dowel bar in the critical funneling region, the skeleton arrangement virtually assures that the bar will not rust freeze to the reinforcing member 14 so that the slabs 10 and 11 will always be free to move towards and away from each other. The washer

23 serves to strengthen and tie the skeleton 21 and the whole arrangement is such that the concrete will flow freely around the assembly without cavitation during the pouring operation. The stresses which are set up in the funneling region are carried into the body of the slab sections by the wings 19 and 20, the bearing plates 22 and the washer 23, as further reinforced by the dowel bar 13. These elements serve to better distribute the imposed loads without setting up critical pressures in the concrete, to more adequately utilize the compressive strength of the concrete, and to develop substantially the maximum shearing strength of the concrete, one of the wings 19 or 20 being always in tension and the other in compression, dependent upon the location of the load and the slab to which it is applied. Any tendency of one of the slabs to move downwardly is resisted by the dowel bar 13, the skeleton structure 21 and the engagement of the wings 19 and 20 with the slabs, and, further, since the skeleton and wings are located above and below the bar, the construction is most efficiently designed to resist the vertical loads commonly encountered in roadways.

In Figs. 5 to 7, inclusive, is illustrated a modification of my improved device which includes the skeleton bearing structure in the funneling region in conjunction with a variant arrangement of load distributing arms or wings. As in Fig. 1, a dowel bar 13 is bridged at mid-depth between slabs 10 and 11 which are separated by an expansion strip 12 through which the bar extends. Associated with the bar on opposite sides of the strip 12 and through which the bar extends is a pair of reinforcing members 28, each of which includes a skeleton structure 29 composed of a washer 30 which is embedded in the joint face of the particular slab, a pair of bearing plates 31—31 each connected at one end to the washer 30 and projecting into the slab in diametral relation on opposite sides of and lying in the vertical plane of the dowel bar 13, and a web 32 connected to the opposite ends of the plates 31 and having a pair of diverging arms 33 and 34 extending into the slab above and below the dowel bar, respectively.

The dowel bar is greased on one side of the strip 12 to prevent bonding with the concrete and relative movements of the slabs 10 and 11 towards and away from each other are accommodated as in Fig. 1 by a cup 35 partially filled with lubricant and into which the greased end of the bar 13 partially extends. Support for the assembly when initially rested on the subgrade is provided by a standard 36 which depends from each washer 30 and carries at its lower end a footing 37 for contact with the subgrade.

The characteristics of this modification are generally identical with that illustrated in Fig. 1. The washer 30 provides lateral reinforcement for the concrete in the funneling region and it, together with the bars 31 and web 32, comprise the skeleton structure 29 which reduces the unit pressure on the concrete and along with the arms 33 and 34 transmits and distributes loads between the dowel bar and slabs into the tension and compression regions of the latter. As before, the skeleton 29 has bearing contact with the dowel bar 13 and rust freezing of the latter is prevented by the nature of its limited contact with the skeleton.

In Fig. 8 which illustrates a modification of the load transfer device shown in Figs. 5 to 7, inclusive, the change consists in reversing the posi-

tions of the web 39 and washer 40, respectively, corresponding to the web 32 and washer 30 in Fig. 6. This arrangement abuts the web 39 against the expansion strip 12 so that it instead of the washer provides lateral restraint for the concrete at the joint face of the slab in the funneling region. Otherwise, the operation and characteristics of this modification are the same as for that shown in Fig. 5. It will be understood that a section along the line 8—8 in Fig. 8 is the same as that shown in Fig. 7, except that the standard 36 depends from the web 39 instead of the washer 40 and hence the web 39 and washer 40 are connected by vertical bearing plates 41 above and below the dowel bar 13 and lying in the vertical plane of the latter and the ends of the web 39 terminate in diverging pairs of arms which extend into the slab above and below the dowel bar, only the upper arms 42 being shown in Fig. 8.

Fig. 9 illustrates a modified arrangement of the reinforcing member 14 shown in Fig. 4 which consists in providing slightly more bearing contact between the dowel bar 13 and skeleton structure 21. Like parts are designated by the same numerals in the two figures. A lower bearing plate 43, corresponding to the lowermost bearing plate 22 in Fig. 4, lies in the vertical plane of the bar, but above the bar, two radial bearing plates 44 are bridged between the plate 43 and washer 23. The plates 44 are positioned on opposite sides of and are symmetrically related to the vertical plane of the bar, the preferred angular relation between the plates being of the order of 45°, or about 22½° on each side of the vertical plane of the bar.

In Figs. 10 to 12, inclusive, is illustrated a further modification of the device. The dowel bar and lubricant filled cup are identical with the form shown in Fig. 5 and are accordingly denoted by the same numerals, as are the slabs and expansion strip. A pair of L-shaped stampings 45 constitute the major reinforcing elements of the structure on each side of the strip and they are positioned to lie in the vertical plane of and above and below the bar, respectively. The vertical limbs 46—46 bear on the dowel bar 13 and their opposite, vertical edges are firmly attached to washers 47 and 48 which also have bearing on the bar with the washer 47 embedded in the joint face of the associated slab and abutting the expansion strip 12. The horizontal limbs 49 act as load distributing arms and respectively extend into the compression and tension regions of the slab. The characteristics and advantages of this arrangement are the same as those described above, with the addition that the use of this shape of stamping provides load distributing arms and bearing plates for the dowel bar in a single element. It will be understood that the limbs 49 need not be horizontal, but may extend into the slab at any angle.

To provide support on the subgrade for the assembly shown in Fig. 10, the ends of the limbs 49 may be enlarged and drilled to receive through the lower limbs only positioning stakes 50, or the indicated ends of the limbs 49 may be simply curled for the same purpose.

Fig. 13 illustrates a further variation of the reinforcing member shown in Fig. 4 wherein additional surface contact of the bearing plates with the dowel bar may be secured even if only two plates are used. Like numerals indicate like parts in both figures. The upper and lower bear-

ing plates are indicated by the numeral 51 and, as in Fig. 4, they lie in the vertical plane of the bar. However, the dowel bar, contacting faces of the plates are coined or upset as at 52 to provide added bearing surface for the bar. Otherwise, the construction is identical with that shown in Fig. 4.

Referring to Figs. 14 to 16, inclusive, there is illustrated a further variation of the device in which the vertical bearing plates are shaped and arranged for tying in with the slabs as load distributing elements, in addition to performing their primary functions. Since the dowel bar and lubricant filled cup are identical with those shown in Fig. 5, they are denoted by the same numerals, as are the slabs and expansion strip. Reinforcing members 53 are located on opposite sides of the strip 12 and each comprises a washer 54 embedded in the joint face of the associated slab and abutting the adjacent side of the strip 12, and diametrically related, bearing plates 55—55 positioned in the funneling region on opposite sides of and in the vertical plane of the bar 13. One end of each bar is firmly attached, as by welding, to the washer 54 and the opposite end is horizontally split for a predetermined distance towards the joint face of the slab to form arms 56—56 which are bent in opposite directions for anchored embedment in the slab and for acting as load distributing elements. This construction provides a pair of such arms above and below the dowel bar on opposite sides of the strip 12. Each washer 54 is preferably provided with a downward extension 54^a which includes an adequate footing 54^b for resting on the subgrade. The characteristics of this modification are the same as those described above.

A further variation is shown in Figs. 17 to 19, inclusive, which bears some similarity to that illustrated in Fig. 14 in respect of the positive anchorage of the bearing in the slabs. The slabs, expansion strip, dowel bar and lubricant filled cup are identified by the same numerals as in Fig. 5. Reinforcing members 57 are positioned on opposite sides of the strip 12 and each comprises a washer 58 embedded in the joint face of the associated slab, diametrically related, bearing plates 59—59 located in the funneling region on opposite sides of and in the vertical plane of the bar 13, the opposite ends of each plate being secured, as by welding, to the washer 58 and a washer 60 inwardly of the slab, and a horizontal element 61 transverse to and extending through each plate 59. Each element 61 extends for the same distance on each side of the associated plate 59 and the ends thereof are preferably enlarged as at 62 to provide anchorage in the slab, thus providing a pair of load distributing arms each above and below the dowel bar on each side of the strip 12. The mode of operation of this arrangement is the same as in the preceding modifications.

In Fig. 20 is illustrated a modified detail which may be employed with any of the other designs. The numeral 63 designates a dowel bar, but instead of associating therewith one or more circular washers as illustrated in the various modifications, a square washer 64 may be used and positioned with its diagonals vertical and horizontal, respectively.

While all of the modifications are indicated as incorporating round dowels, it will be understood that the shape of this bar may be varied as desired, including those having square and rectangular cross sections and sections other than

round which are characterized by continuous lateral surfaces. Further, in all variations of the device, both ends of the dowel bar may be greased, if desired.

From the foregoing, it will be understood that all of the above described modifications have certain characteristics in common, namely, the use of a skeleton structure in the funneling region of the slab which provides adequate bearing for the dowel bar and insures a reduction in the unit pressure on the concrete around the bar during load transfer, a substantial freedom from rust freezing of the dowel which would otherwise lock the adjacent slabs against relative movement lengthwise of the roadway and cause fracture of the concrete, a definite lateral support for the concrete around the dowel at the joint face of each slab, and an effective distribution of the applied load from one slab to the next.

I claim:

1. A load transfer device for concrete slab joint construction comprising a dowel bar, and a pair of spaced, skeleton, reinforcing structures surrounding the bar at an intermediate part thereof, each structure including spaced plate means through which the bar extends in bearing relation thereto, one of the plate means being adapted for embedment in the joint face of the associated slab and rib-like bearing plates extending between the plate means above and below and having edge contact only with the bar.

2. A load transfer device for concrete slab joint construction comprising a dowel bar, and a pair of spaced, skeleton, reinforcing structures surrounding the bar at an intermediate part thereof, each structure including spaced plate means through which the bar extends in bearing relation thereto, one of the plate means being adapted for embedment in the joint face of the associated slab, a rib-like bearing plate extending between the plate means below and lying in the vertical plane of the bar, and a pair of rib-like bearing plates extending between the plate means above and radially related to and symmetrically positioned on opposite sides of the vertical plane of the bar, all of the bearing plates having edge contact only with the bar.

3. A load transfer device for concrete slab joint construction comprising a dowel bar, a pair of spaced, skeleton, reinforcing structures surrounding the bar at an intermediate part thereof, each structure including spaced plate means through which the bar extends in bearing relation thereto, one of the plate means being adapted for embedment in the joint face of the associated slab, rib-like bearing plates extending between the plate means above and below and having edge contact only with the bar, and stress carrying arms extending from said one plate means above and below the bar.

4. A load transfer device for concrete slab joint construction comprising a dowel bar, and a pair of spaced, skeleton, reinforcing structures surrounding the bar at an intermediate part thereof, each structure including first and second, spaced plate means through which the bar extends in bearing relation thereto, the first plate means being adapted for embedment in the joint face of the associated slab, rib-like bearing plates extending between the plate means above and below and having edge contact only with the bar, and stress carrying arms extending from the second plate means above and below the bar.

5. A load transfer device for concrete slab joint construction comprising a dowel bar, and a pair

of spaced, skeleton, reinforcing structure surrounding the bar at an intermediate part thereof, each structure including spaced plate means through which the bar extends in bearing relation thereto, one of the plate means being adapted for embedment in the joint face of the associated slab, and a pair of stress carrying, L-shaped, flat and relatively thin members positioned, respectively, above and below and in the vertical plane of the bar, the vertical limbs of each member having their vertical edges firmly secured to the opposed faces of the plate means and their inner horizontal edges having bearing contact with the bar, and the horizontal limbs of the members being adapted to extend into the associated slab. 15

6. A reinforcing member for concrete slab joint construction having a dowel bar bridged between adjoining slabs comprising spaced, plate means apertured to bearingly receive the bar, one of the plate means being adapted for embedment in 20 the joint face of the associated slab, and rib-like bearing plates extending between the plate means

above and below the apertures, the facing edge surfaces of the bearing plates being continuations of the adjacent surface portions of the apertures.
